UNITED STATES PATENT OFFICE

FREDERICK C. SCHRAMM AND MAX DACH, OF FLUSHING, NEW YORK

CARBURETOR

Application filed April 22, 1931. Serial No. 532,042.

This invention pertains to charge forming devices for internal combustion motors and more particularly it pertains to novel constructions in jet tubes for carburetors.

5 It is one of the objects of the present invention to provide a novel construction of jet tube for carburetors wherein a breaking up of the fuel, to a very high degree, is obtained thus producing a high degree of 10 vaporization.

A feature of the invention resides in a novel construction whereby the stream of gasoline is subjected to one or more cross currents of air preferably just immediately before it is 15 discharged from the fuel jet of the carburetor.

Another feature of the invention resides in a novel construction of discharge jet which may be incorporated in any of the standard 20 types of carburetors operating either on the vertical, horizontal, angular or down draft principle.

Still another feature of the invention, resides in the provision of means whereby a 25 stream of gasoline or other fuel is intercepted by one or more streams of air which are introduced tangentially into the fuel stream.

Other features of the invention relate to 30 certain novel and improved constructions, arrangements and combinations of parts hereinafter described and particularly pointed out in the claims, the advantages of which will be readily understood and appreciated by those skilled in the art.

35 The invention will be clearly understood from the accompanying drawings illustrating the invention in its preferred forms and the following detailed description of the constructions therein shown.

40 In the drawings:

Figure 1 is a view in side elevation partly broken away illustrating a conventional carburetor with a fuel supply jet constructed 45 in accordance with one form of the invention in operative position therein,

Figure 2 is a detail longitudinal sectional view of that form of jet illustrated in Figure 1,

50 Figure 3 is a top plan view thereof,

Figure 4 is a horizontal sectional view taken on the line 4-4 of Figure 2,

Figure 5 is a view partly in elevation and partly in longitudinal section of a modified 55 form of the invention,

Figure 6 is a horizontal sectional view taken on the line 6-6 of Figure 5,

Figure 7 is a fragmentary sectional view of the Venturi passage of a carburetor of the down draft type illustrating a form of 60 nozzle constructed in accordance with the present invention in position therein,

Figure 8 is a view partly in elevation partly in section of that form of nozzle illustrated in Figure 7,

Figure 9 is a transverse sectional view taken on the line 9-9 of Figure 7, and

Figure 10 is an enlarged detail sectional view taken substantially on line 10-10 of 70 Figure 9.

Referring more particularly to the drawings, and with special reference to Figures 1 to 4 inclusive, the reference numeral 20 designates a carburetor having a float chamber 21, and an air intake 22 controlled by a suitable butterfly valve mounted upon a shaft 23 and not shown. The reference character 24 designates the mixture outlet passage controlled by a suitable butterfly valve in the ordinary manner. The reference character 25 designates the mixing chamber of the carburetor and 60 designates the fuel supply nozzle constructed in accordance with that type of the invention illustrated in Figures 2 to 4.

Referring particularly to Figures 1 to 4, it will be noted that the fuel nozzle comprises a relatively long tube 60 having an enlarged head 61 which is hollow, and has its upper end closed as at 62. The enlarged head 60 is so formed as to present a shoulder or the like 65 in the path of air as it passes into the mixing chamber 25 of the carburetor, and this shoulder serves to retard the air in its passage and cause the same to pass through a plurality of air passages 65 which are angularly disposed with respect to the axis of the passage through the nozzle 60. Fuel is admitted to the passage 30 leading through the nozzle 60 in any desired manner at the 95 100

lower end 31 thereof and in operation, the fuel in passing upwardly through the passage 30 of the nozzle 60 is discharged through a plurality of minute openings 63 at the upper end 62 thereof and also through passages 64 provided in the side walls of the enlarged head portion into the mixture fuel chamber 25 at the passage 24 of the carburetor. In its passage through the nozzle 60, and just prior to its discharge through the passages 63, 64, the stream of fuel is intercepted by a plurality of streams of air which are admitted into the hollow head through the passages 65 formed in the shoulder 66 and projected into the fuel at an angle thereto thus causing a thorough breaking up of the fuel and intermingling of air therewith to provide the highly combustible and therefore economical fuel.

By reference to the drawings, it will be noted that in each of the forms, means projects into the path of the air in its passage through the carburetor and serves to retard the same thus causing it to pass through the air passages with considerable force, and while various constructions are herein illustrated, it will be noted that this feature is common to all of the forms illustrated and thus in all the forms, means to insure an interception of the fuel stream by a plurality of air streams of sufficient force to cause a thorough breaking up of the fuel stream and intermingling of air therewith is provided.

In that form of the invention illustrated in Figures 5 and 6, the nozzle is constructed on a slightly different principle than in the heretofore described form of the invention. In this form illustrated in Figures 5 and 6, the air is introduced into the fuel stream of the jet tangentially thereof and the stream of mixed fuel and air which is emitted from the jet, is by this construction given a whirling or rotary motion which tends to even more thoroughly break up the fuel and cause a thorough mixing of the air therewith.

In this form of the invention, the upper end of the nozzle or jet 50 is closed as at 51, it being understood of course that as in the heretofore described form of the invention the nozzle or jet has an enlarged head 52 which presents a shoulder 53 in the air passage through the carburetor in order to cause a banking up of the air stream at this point and thus insure its passage through a plurality of air passages 54 which communicate with fuel passages 55 which pass angularly through the enlarged head 52 of the jet or nozzle. As best illustrated by the arrows A in Figure 5, and as also clearly shown in Figure 6, these air passages 54 are arranged angularly or spirally around the head of the nozzle or jet 50 and lead from a point beneath the shoulder 53 of the head 51 of the nozzle to the radially extending passages 55 through which the fuel is emitted from the nozzle or jet.

Thus it will be apparent that the fuel in its

passage through the nozzle or jet 50 is just prior to its discharge therefrom through the passages 55 subjected to the action of a plurality of streams of air which are projected into the fuel stream tangentially thereof thus giving the same a whirling motion and causing a thorough breaking up of the element thereof and a thorough intermingling of air and fuel to provide a highly combustible fuel.

In Figures 7 to 10 inclusive, we have illustrated a carburetor of the down draft type, and in said figures 70 designates the air intake passage of such a carburetor, and 71 designates the Venturi passage thereof. Projecting into the Venturi passage 71 at an angle thereto, there is a fuel supply nozzle 72 and as best illustrated in Figures 7 and 10, this nozzle 72 has a stem portion 73 and a head portion 74 the nozzle being of substantially T-shape. The head portion 74 projects transversely of the Venturi passage 71 as best illustrated in Figure 9 and it is provided with a plurality of passages 76 and 77, the passages 76 being staggered or offset with relation to the heretofore mentioned passages 77 which latter are in the underneath side of the head 74.

In this connection, and as best shown in Figure 9, the length of the head 74 of the nozzle is substantially equal to the diameter of the air passage 71 at the smallest diameter of the Venturi passage.

Thus it will be apparent that even in this form of the invention, the air in its passage through the Venturi passage 71 of the carburetor will be retarded and will be caused to flow through the openings 76 and in through the opening 77 picking up the gasoline or other fuel and causing a thorough breaking up thereof and an intermingling thereof with the said air.

In each of the forms of the invention herein illustrated, it will be noted that the air stream is projected through the fuel stream, and that the fuel stream is projected through the air stream, and also that this action takes place at a point above the normal liquid level of the fuel in the jet, as well as the discharge head, crown or tip of the jet.

From the foregoing, it will be apparent that the present invention provides a new and novel construction in carburetors wherein a thorough mixing of air and fuel to the desired end of a highly combustible fuel is obtained, and that the construction herein illustrated is capable of use in practically all standard types of carburetor merely by introducing a nozzle constructed in accordance with one of the forms of this invention thereinto.

While the invention has been herein illustrated in its preferred forms, it is to be understood that the invention is not to be limited to the specific construction herein shown,

and that it may be practiced in other forms without departing from the spirit thereof.

Having thus described the invention, what is claimed as new and what it is desired to secure by Letters Patent of the United States, is:

1. In a carburetor, an air passage extending therethrough, a fuel jet positioned in said passage, said fuel jet having a closed upper end, an enlarged portion formed on the upper end of said fuel jet, said enlarged portion extending into said air passage to retard the flow of air therethrough, discharge passages extending through the side walls of said jet near the upper end thereof, said passages discharging into said air passage, and a plurality of relatively small air passages formed in said jet and discharging tangentially into said jet discharge passages, said air passages having their inlet ends located on the exterior of the jet at the base of the enlarged portion thereof.

2. In a carburetor, an air passage extending therethrough, a fuel jet extending angularly into said air passage, and a plurality of air passages extending through the walls of the fuel jet, the axis of said air passages being parallel to the axis of the air passage through the carburetor.

3. In a carburetor, an air passage extending therethrough, a T-shaped fuel jet extending angularly into said air passage, with the head of said jet disposed substantially at right angles to the axis of the air passage through the carburetor, and a plurality of air passages passing through the head of the T-shaped jet in parallelism with the axis of the air passage through the carburetor.

4. In a carburetor, an air passage extending therethrough, a T-shaped fuel jet projecting into said air passage at an angle to the axis thereof, the length of the head of said fuel jet being substantially equal to the diameter of said air passage, and a plurality of air passages extending through the head of the jet.

5. In a carburetor, an air passage extending therethrough, a venturi forming a portion of said air passage, a T-shaped fuel jet extending angularly into said venturi, the head of said fuel jet being of a length substantially equal to the smallest transverse dimension of said venturi, and a plurality of air passages extending through the head of the fuel jet.

6. In a carburetor, an air passage extending therethrough and a fuel jet arranged therein, said fuel jet comprising a tubular body portion having an enlarged hollow head presenting an abrupt shoulder in said fuel passage, relatively small passages extending through said shoulder into the hollow head, and relatively small discharge passages extending through the side walls of the head.

7. In a carburetor, an air passage extend-

ing therethrough and a fuel jet arranged therein, said fuel jet comprising an elongated hollow body terminating at its upper end in an enlarged head of hollow truncated conical form, and presenting an abrupt shoulder in the fuel passage, discharge passages leading through the side walls of said head, and relatively smaller passages leading through said shoulder and discharging directly into said discharge passages.

8. In a carburetor, an air passage extending therethrough and a fuel jet arranged therein, said fuel jet comprising an elongated hollow body terminating at its upper end in an enlarged head of hollow truncated conical form, and presenting an abrupt shoulder in the fuel passage, discharge passages leading through the side walls of said head, and relatively smaller passages leading through said shoulder and discharging directly into said discharge passages, said last mentioned passages extending tangentially of the said shoulder.

In testimony whereof we affix our signatures.

FREDERICK C. SCHRAMM.
MAX DACH.
